UNITED STATES PATENT OFFICE.

EDWARD FREESE, OF NEW YORK, N. Y., ASSIGNOR OF ONE-HALF TO
HERMAN MÜNDHEIM, OF SAME PLACE.

NON-REFILLABLE BOTTLE.

SPECIFICATION forming part of Letters Patent No. 626,417, dated June 6, 1899.

Application filed November 16, 1898. Serial No. 696,584. (No model.)

To all whom it may concern:

Be it known that I, EDWARD FREESE, a citizen of the United States, and a resident of New York city, county and State of New York, 5 have invented new and useful Improvements in Non-Refillable Bottles, of which the following is a specification.

This invention relates to a non-refillable bottle provided with an inner freely-suspended tubular valve-chamber which will remain in an upright position when the bottle is inclined within certain limits, and thus insures the seating of the valve.

In the accompanying drawings, Figure 1 is a 15 longitudinal central section of my improved non-refillable bottle; Fig. 2, a cross-section on line 22, Fig. 1. Fig. 3 is a longitudinal section of the upper part of the bottle, showing the valve open; and Fig. 4, a longitudinal section of the upper part of the bottle, showing a modification of the invention.

The letter A represents a bottle, into the neck a of which is permanently fitted a tubular sleeve b, having a number of partitions or 25 guards b' b² b³, that extend partly across the sleeve to prevent access to the interior of the bottle. The guards b' b³, projecting from one side of the sleeve, are horizontal, while the guard b, projecting from the opposite side, is 30 inclined and extends with its free end between the guards b' b³, thus providing a large discharge-channel between them.

c is a freely-suspended swinging tubular valve-chamber hung within the lower portion 35 of neck a, below the sleeve b, and projecting into the bottle A in such a manner that it can tilt in any direction. To this effect the tube is suspended within the neck by a ball-and-socket joint, the ball or swelling c' being 40 formed on the upper part of the tube, while the socket is shown to be formed partly within the neck a and partly within the sleeve b.

Within the tube c is contained a ball-valve 45 d, normally seated upon the lower contracted end of the tube, as at c². Below the valve-seat the tube is provided with a flaring nozzle c³, which is adapted to lie flush against the inner side of the bottle A when the latter is inclined below a horizontal plane, Fig. 3, 50 and thus guides the liquid into the tube. The upper portion of the tube c has an in-

creased bore and is provided with a number of inner radial ribs c⁴, between which discharge-ducts c⁵ are formed.

When the bottle is held with its neck downward, Fig. 3, the valve d will leave its seat and the liquid can be freely poured out. 55

If the bottle is held in an inclined position with the neck pointing upward, the tube c will at once swing so as to retain an upright position, and thus cause the valve d to remain settled upon its seat c². In this way it will be seen that spurious refilling of the bottle is practically prevented.

In Fig. 4 the ball-and-socket joint is replaced by an annular flexible diaphragm e, by which the tube is so suspended from the bottle that it will swing into an upright position when the bottle is inclined. 65

What I claim is—

1. A non-refillable bottle provided with an inner freely-suspended valve-chamber, and a valve within such chamber, substantially as specified.

2. A non-refillable bottle provided with an inner freely-suspended tubular valve-chamber, an inclosed valve, and a guard above such chamber, substantially as specified. 75

3. A non-refillable bottle provided with an inner freely-suspended tubular valve-chamber having a series of ribs and intervening ducts at its upper end, an inclosed valve, and a series of guards above such chamber, substantially as specified. 80

4. A non-refillable bottle provided with an inner freely-suspended tubular valve-chamber having a lower flaring nozzle, a valve-seat above such nozzle, and an inclosed valve, substantially as specified. 85

5. A non-refillable bottle provided with an inner freely-suspended tubular valve-chamber having a lower flaring end, upper ribs and intervening ducts, an inclosed valve, and a series of guards above the chamber, one of the guards being inclined and projecting with its free end between the other guards, substantially as specified. 90

EDWARD FREESE.
